PIVOTED OUTER JAW WRENCH

Charles H. Ortman, Chardon, Ohio

Application January 10, 1946, Serial No. 640,327

10 Claims. (Cl. 81—103)

1

This invention relates to clamping devices of the type wherein a movable jaw is adjusted toward and from a fixed jaw carried by a base and is retained in any desired clamping relation with respect to the fixed jaw by means of a locking device such as a pawl, resiliently mounted on the base and having (when a pawl is used for such device) one or more teeth adapted to engage spaced elements carried by an extension of the movable jaw by which the latter is supported by the said base for movement toward and from the fixed jaw.

In its embodiment shown herein, the clamping device appears as a type of wrench known to the trade as a "pipe wrench," and the terms by which various parts of my embodiment are designated are the terms customarily employed in connection with such wrenches but without any intention of excluding from the scope of my invention any other embodiments of the same.

The general purpose and object of my invention is to provide a construction of clamping device of the character shown and described whereby the movable jaw may be conveniently moved toward and from the fixed jaw; also to provide novel and efficient means whereby a final clamping movement may be imparted to the movable jaw where the spacing of the ratchet teeth is such, in a given case, as to prevent a tight gripping action to be obtained; also to provide means normally tending to produce a narrower space between the outer ends of the jaws than between the inner ends thereof whereby a firm gripping action may be exerted upon an object by the outer ends of the said jaws as well as by the inner ends of the same.

Further and more limited objects of my invention will be realized in and through the construction and arrangement of the parts thereof as will be set forth in the specification hereinafter and as are shown in the drawings, wherein Fig. 1 represents a side sectional elevational view of a wrench embodying my invention, the handle being broken away; Fig. 2 is a top plan view of a portion of the handle and of the operating parts of the wrench attached thereto; Fig. 3 a bottom plan view; Fig. 4 a sectional view taken on the line 4—4 of Fig. 1, looking in the direction of the arrows; and Fig. 5 an elevational view of the cam showing the positions of the shoulder and the "low" portion of the cam; and Fig. 6 is a perspective view of the control cam.

Describing the various parts herein by reference characters, 10 denotes a base, shown specifically as the handle of a wrench, which has a 55

2

fixed jaw 11, preferably formed therewith. The front end of the base or handle is provided with a passageway 12 extending through the jaw 11 proper. A slot 13 is formed between the side members 14 which extend rearwardly from the fixed jaw and which provide a space for the reception of the shank 15 which carries at its forward end, and preferably formed therewith, a movable jaw 16. The jaws 11 and 16 are provided with oppositely extending ratchet-like gripping teeth 11^a and 16^a, respectively, and the outer ends of the teeth 16^a lie within a rearwardly concave surface. 17 denotes a sleeve which is provided with a guideway therethrough adapted to register with the passageway 12 and in which the shank 15 is slidably mounted. This sleeve is provided with a downwardly extending front extension 18 and with a downwardly extending rear extension 19, the said extensions providing therebetween a space 20, within the upper portion of which there project spaced engageable elements 15^a, shown as ratchet teeth and carried by the shank 15.

21 denotes a shaft, the front end of which is shown as threaded into the extension 18 and the rear end of which is mounted within the extension 19 and which shaft extends substantially parallel with the plane of the ratchet teeth 15^a.

22 denotes controlling means, said means being shown as a cam which is generally cylindrical in shape throughout the major portion of its length and which is mounted upon the shaft 21 and which has a forward base 23 extending transversely of the shaft and adapted to engage the vertical wall 18^a at the rear of the forward extension 18 of the sleeve 17, the diameter of the cam being such as to enable it to clear the ratchet teeth. The rear operating portion of the cam is shown as consisting generally of two cooperating sections. The first section is a short section 24 the surface of which is substantially parallel with the forward base 23 of the cam and which constitutes the "low" portion of the rear surface of the cam, which section is the one nearest to said forward base. The second section 25 has a spiral operating surface, and a shoulder 26 extends from the "high" end of the surface of the cam to the "low" surface of the cam. The cam is also provided with a locking device 27 for holding the teeth of the pawl (to be described) in engagement with the ratchet teeth when the cam is rotated to a position to enable the nose of the pawl to engage the surface 25 of the cam. The exterior of this locking device is cylindrical throughout the major portion thereof, the ends

of the cylindrical portion being connected by a plane portion 27^a which, except at its junction with the cylindrical surface, is nearer to the axis of rotation than is the cylindrical surface. This plane surface is substantially co-extensive in angular extent with the section 24 of the cam. The cam as shown and described herein is substantially the same as that shown and described in my copending application Serial No. 585,460, filed March 29, 1945.

28 denotes a locking element shown as a pawl provided with a plurality of teeth 28^a adapted to mesh with the ratchet teeth. The pawl is provided with a front or nose 28^b which is adapted to be engaged by the spiral operating surface 25 of the cam and is also provided with a tail 29 extending between the top of a transverse wall 30 in the rear sleeve extension 19, with a running clearance between the tail of the pawl and the ratchet teeth 15^a. The pawl is also provided with an arm 31 extending downwardly therefrom and provided with an opening for the reception of the shaft 21, the arm 31 being extended and rearwardly curved to provide a gripping end portion 31^a. 32 denotes a coil spring which is mounted on the shaft 21 between the pawl arm 31 and the sleeve extension 19, whereby the pawl is resiliently and rockably mounted upon the shaft and the rear sleeve extension.

33 denotes a narrow stop wall extending from and connecting the bottoms of the side members 14 and adapted to be engaged by the lower surface of the shank 15 when the movable jaw is in its extreme forward position and the rear end of the shank is depressed. The movement of the jaw and shank in such forward direction is arrested by the engagement of a stud 15^c, serving as a thumb piece and connected to the rear upper end of the shank with a narrow stop wall 34 extending from and connecting the upper ends of the side members 14. The rear portion of the top of the sleeve 17 is provided with a slot 35, in front of a transversely extending wall 36 at the rear end of the sleeve top, for the slidable anchorage of the rear end of a flat spring 37, the front end of which is secured to the top of the fixed jaw 11, as by means of a screw 38. This spring is upwardly curved whereby it normally lifts the rear end of the sleeve 17 and the shank 15 within said sleeve until the rear end of the top of the sleeve engages the stop wall 34. When the parts are in this position, the gripping portion 16^a of the movable jaw 16 will be nearly parallel with the gripping portion 11^a of the fixed jaw 11, with the lower end of the former gripping surface being inclined toward the lower end of the latter gripping surface.

With the parts constructed and arranged as described, and assuming that it is desired to apply the jaws to an object to be grasped or clamped thereby, the movable jaw can be moved beyond the fixed jaw a sufficient distance to enable the object to be received between the said jaws. This movement can be effected when the "lower" portion of the cam is adjacent to the nose of the pawl, which will enable the teeth of the pawl to be disengaged from the ratchet teeth 15^a by operating the finger grip 31^a. The movable jaw can then be retracted toward the fixed jaw by pulling rearwardly upon the stud 15^c. Assuming that the object is not tightly clamped between the two jaws and that the distance which the movable jaw must be moved in order to insure such clamping is less than the distance between adjacent ratchet teeth on the shank 15, the opera-

tor may then impart this additional movement to the movable jaw by rotating the cam so that the spiral operating surface thereof engages the nose of the resiliently mounted pawl, which will result in a thrust being imparted in a rearward direction to the movable jaw by the engagement of the forward base 23 of the cam with the rear of the front sleeve extension 18, the spring 32 being compressed by this action between the arm 31 of the pawl and the rear extension 19 of the sleeve 17. The movable jaw may be retracted as far as desired toward the fixed jaw by means of the finger-grip stud 15^c. The sleeve, meanwhile, is held against forward movement during the forward movement of the shank and movable jaw by engagement of the upper front end 17^c thereof with the rear wall 11^c of the top of the fixed jaw and against rearward movement during the rearward movement of the said shank and jaw by engagement of the rear sleeve extension 19 with the wall 33, there being a sufficient longitudinal distance between these walls to permit of the rocking movement of the sleeve due to the rocking movement of the shank 15.

When it is desired to release the jaws from a pipe or other object grasped therebetween, the operator can press downwardly the rear of the shank 15, which will rock the jaw 16 upwardly and thereby provide clearance between the jaws which will permit such releasing movement.

For convenience of description, the parts of the specific form of clamping device (wrench) shown herein are assumed to be in the positions which they occupy in Figs. 1 and 4, and the terms "top," "bottom," "front," "rear" and "side" have been employed herein and will also be employed in certain of the claims hereinafter in designating the positions of the parts, but without any intention thereby of limiting the positions which these parts will actually assume in operation.

Having thus described my invention, what I claim is:

1. A device of the character described comprising a base having a fixed jaw attached thereto and provided with side walls extending longitudinally thereof away from said jaw and providing a space therebetween, a sleeve member mounted in said space and having a passageway therethrough, a shank extending through said sleeve member and provided with a jaw and having ratchet teeth thereon, said sleeve member having longitudinally spaced extensions projecting beyond the ratchet teeth on said shank, a shaft supported by said extensions substantially parallel with and spaced from said ratchet teeth, a rotary cam on said shaft having an inclined operating surface, a pawl having one or more teeth thereon adapted to engage teeth on said ratchet and having a nose adapted to be engaged by the inclined operating surface of said cam, spring means tending to hold the tooth or teeth on the pawl in engagement with the teeth of the ratchet, and means for disengaging the tooth or teeth of the pawl from the teeth of the ratchet when the nose of the pawl is out of engagement with the operating surface of the cam.

2. A device of the character described comprising a base having a fixed jaw attached thereto and extending downwardly therefrom and provided with a space therein extending longitudinally thereof away from said jaw, a sleeve member rockably mounted in said space and having a passageway therethrough, a shank in said space and extending through the passageway in said sleeve member and provided with a jaw

extending downwardly therefrom and having ratchet teeth on its under surface, said sleeve member having front and rear downward extensions projecting beyond the ratchet teeth on said shank, a shaft supported by said extensions substantially parallel with and spaced from said ratchet teeth, a pawl having one or more teeth thereon adapted to engage teeth on said ratchet, said pawl having an arm extending therefrom and provided with an opening for the passage of the shaft therethrough, a coil spring on said shaft interposed between the arm of said pawl and the rear sleeve extension and tending to hold the tooth or teeth of the pawl in engagement with the teeth of the ratchet, said arm being provided with an operating extension whereby the tooth or teeth thereon may be disengaged from the ratchet teeth, and means on said shaft rotatable into and out of engagement with the lower surface of the pawl thereby to lock and unlock the tooth or teeth thereof to and from the ratchet teeth.

3. A device of the character described comprising a base having a fixed jaw attached thereto and extending downwardly therefrom and provided with a space therein extending longitudinally thereof away from said jaw, a sleeve member rockably mounted in said space and having a passageway therethrough, a shank in said space and extending through the passageway in said sleeve member and provided with a jaw extending downwardly therefrom and having ratchet teeth on its under surface, said sleeve member having front and rear downward extensions projecting beyond the ratchet teeth on said shank, a shaft supported by said extensions substantially parallel with and spaced from said ratchet teeth, a rotary cam on said shaft having an inclined operating surface at the rear thereof and a front bearing portion adapted to bear against the rear of the front extension of said sleeve member, a pawl having one or more teeth thereon adapted to engage teeth on said ratchet and having a nose adapted to be engaged by the inclined operating surface of said cam, said pawl having an arm extending therefrom and provided with an opening for the passage of the shaft therethrough, a coil spring on said shaft interposed between the arm of said pawl and the rear sleeve extension and tending to hold the tooth or teeth of the pawl in engagement with the teeth of the ratchet, said arm being provided with an operating extension whereby the tooth or teeth on said pawl may be disengaged from the ratchet teeth when the nose of the pawl is out of engagement with the operating surface of the cam and the operating surface serving to lock the tooth or teeth of the pawl in engagement with teeth on the ratchet.

4. A device of the character described comprising a base having a fixed jaw attached thereto and provided with a passageway in the jaw-carrying portion thereof merging with a vertically extending slot provided between opposed side portions of the base, a sleeve member located within the slot and having a passageway adapted to register with the former passageway, said sleeve member having front and rear extensions projecting downwardly beyond the bottom of the slot, a shank slidably mounted in said passageways and provided with ratchet teeth on its lower surface and having a jaw at the front end thereof, a shaft mounted in said front and rear extensions of the sleeve member below and substantially parallel with the ratchet teeth on said shank, a pawl hav-

ing a tooth or teeth thereon adapted to engage teeth on the ratchet and provided with an arm having an aperture therethrough through which the shaft extends, a coil spring interposed between the rear surface of said arm and the front surface of the rear sleeve extension, a cam mounted for rotation on said shaft in front of the arm of said pawl and having an inclined operating surface adapted to engage the front or toe of the pawl thereby to hold the tooth or teeth of the same in engagement with the teeth on the ratchet and also having a front bearing portion adapted to engage the rear of the front sleeve extension when the inclined operating surface of the cam is in engagement with the toe of the pawl.

5. A device of the character described comprising a base having a fixed jaw attached thereto and provided with a passageway in the jaw-carrying portion thereof merging with a vertically extending slot provided between opposed side portions of the base, a sleeve member located within the slot and having a passageway adapted to register with the former passageway, said sleeve member having front and rear extensions projecting beyond the bottom of the slot, a shank slidably mounted in said passageways and provided with ratchet teeth on its lower surface and having a jaw at the front end thereof, a shaft mounted in said front and rear extensions of the sleeve member below and substantially parallel with the ratchet teeth on said shank, a pawl having a tooth or teeth thereon adapted to engage teeth on the ratchet and provided with an arm having an aperture therethrough through which the shaft extends, a coil spring interposed between the rear surface of said arm and the front surface of the rear sleeve extension, a cam mounted for rotation on said shaft in front of the arm of said pawl and having an inclined operating surface adapted to engage the front or toe of the pawl thereby to hold the tooth or teeth of the same in engagement with the teeth on the ratchet and also having a front bearing portion adapted to engage the rear of the front sleeve extension when the inclined operating surface of the cam is in engagement with the toe of the pawl.

6. In the device set forth in claim 5, the sleeve member being provided adjacent to the rear and upper end thereof with an anchorage and the spring means comprising a flat spring connected at one end to said anchorage and at its opposite end to an anchorage on the base in front of the former anchorage, there being a sliding connection between one of said anchorages and the end of the spring which cooperates therewith.

7. A device of the character described comprising a base having a fixed jaw attached thereto and extending downwardly therefrom and provided with a space therein extending longitudinally thereof away from said jaw, a sleeve member rockably mounted in said space and having a passageway therethrough, a shank in said space and extending through the passageway in said sleeve member and provided with a jaw extending downwardly therefrom and having ratchet teeth on its under side, said sleeve member having front and rear downward extensions projecting beyond the ratchet teeth on said shank, a shaft supported by said extension substantially parallel with and spaced from and below said ratchet teeth, a pawl having one or more teeth thereon adapted to engage teeth on

said ratchet and having an arm extending therefrom and provided with an opening for the passage of the shaft therethrough, a coil spring on said shaft interposed between the arm of said pawl and the rear sleeve extension and tending to hold the tooth or teeth of the pawl in engagement with the teeth of the ratchet, the arm of the pawl being provided with a finger-gripping extension and the rear of the upper portion of the shank having a projection adapted to be grasped by the thumb of the operator.

8. A device of the character described comprising a base having a fixed jaw attached thereto and provided with a passageway in the jaw-carrying portion thereof merging with a vertically extending slot provided between opposed side portions of the base, a sleeve member located within the slot and having a passageway adapted to register with the former passageway, said sleeve member having front and rear extensions projecting downwardly therefrom, a shank slidably mounted in said passageways and provided with ratchet teeth on its lower surface and having a jaw at the front thereof, a shaft mounted in said front and rear extensions of the sleeve member below and substantially parallel with the ratchet teeth on said shank, a pawl having a tooth or teeth thereon adapted to engage teeth on the ratchet and provided with an arm having an aperture therethrough through which the shaft extends, a coil spring interposed between the rear surface of said arm and the front surface of the rear sleeve extension, and spring means connected at one end to the base and having its opposite end operatively connected with the rear portion of the sleeve member there-

by to normally hold the rear portion of the sleeve member elevated.

9. In the device set forth in claim 8, the arm of the pawl being provided with a finger gripping projection and the rear of the upper portion of the shank having a projection adapted to be grasped by the thumb of the operator.

10. In the device set forth in claim 8, there being a projection, carried by the upper portion of one of the side walls which define the slot, for engaging the rear upper portion of the sleeve member to limit the upward movement thereof by the spring and there being a stop carried by the lower portion of one of said side walls and adapted to be engaged by the lower portion of the shank, thereby to limit the downward rocking movement of the rear portion of said sleeve member when said rear portion is depressed against the action of said spring.
